(57) **CLAIM**

The ornamental design for an oral care implement, as shown and described.

DESCRIPTION

FIG. 1 is a perspective view of a first embodiment of the new design;

FIG. 2 is a right side view thereof;

FIG. 3 is a front view thereof;

FIG. 4 is a top view thereof;

FIG. 5 is a bottom view thereof;

FIG. 6 is a perspective view of a second embodiment of the new design;

FIG. 7 is a right side view thereof;

FIG. 8 is a front view thereof;

FIG. 9 is a top view thereof; and,

FIG. 10 is a bottom view thereof.

All broken lines shown in the drawings illustrate portions of the oral care implement that form no part of the claimed design.
